DESIGN FOR A FOUNTAIN PEN OR SIMILAR ARTICLE

Harold W. Pearce, West Barrington, R. I., assignor to Welsh Manufacturing Company, a corporation of Rhode Island

Application March 24, 1937, Serial No. 68,384

Term of patent 14 years

To all whom it may concern:

Be it known that I, Harold W. Pearce, a citizen of the United States, residing at West Barrington, in the county of Bristol and State of Rhode Island, have invented a new, original, and ornamental Design for a Fountain Pen or Similar Article, of which the following is a specification, reference being had to the accompanying drawing, forming a part thereof.

Fig. 1 is a front elevation;

Fig. 2 is an edge elevation;

Fig. 3 is a top end view looking in the direction of the indicating arrows on line 3—3 of Fig. 2; and

Fig. 4 is a bottom end view of a fountain pen or similar article, looking in the direction of the indicating arrows on line 4—4 of Fig. 2.

The dominant feature of the design is shown in full lines.

I claim:

The ornamental design for a fountain pen or similar article substantially as shown and described.

HAROLD W. PEARCE.
